[57] CLAIM

The ornamental design for a switchgear contact, as shown and described.

DESCRIPTION

FIG. 1 is a perspective view of a switchgear contact showing our new design;

FIG. 2 is a side elevational view thereof;

FIG. 3 is a side elevational view of the side opposite that shown in FIG. 2;

FIG. 4 is an end elevational view thereof;

FIG. 5 is an end elevational view of the end opposite that shown in FIG. 4;

FIG. 6 is a top plan view thereof;

FIG. 7 is a bottom view thereof; and

FIG. 8 is a side elevational view corresponding to FIG. 2, drawn to a reduced scale, and showing related components of a switchgear assembly in dashed lines to illustrate environmental structure. The broken line showing forms no part of the claimed design.
